UNITED STATES PATENT OFFICE

2,505,387

SOAP TRAY

Cecil Herman Dantzler, Chickasaw, Ala.

Application March 2, 1946, Serial No. 651,522

1 Claim. (Cl. 45—28)

1

This invention relates to improvements in soap trays or receptacles.

An object of the invention is to provide improved forms of soap trays or receptacles formed with fluted base sections and integrally formed fluted shield or back sections, together with drain receptacles formed at the ends of said base sections, and said flutes being angled so that water on a cake of soap when placed in any one of said receptacles will drain toward the end water receiving receptacles.

Another object of the invention is to provide an improved integrally formed soap tray or receptacle including base and shield or back sections being formed to provide inclined flutes for directing water from a cake of soap to the ends of the tray or receptacle into water collecting compartments or receptacles formed at the opposite ends of said soap tray or receptacle.

A further object of the invention is to provide an improved molded or cast integrally formed soap tray or receptacle which will be highly efficient in use, and relatively inexpensive to manufacture and produce.

Other objects will appear as the description proceeds.

In the accompanying drawings which form a part of this application,

Figure 1 is a plan view of one form of improved soap tray in which the flutes on the back or shield are angled forwardly from the top to the bottom and are connected with the flutes on the bottom of the tray which are sloped from the front to the rear thereof, while the troughs between the flutes on said bottom slope from the back to the front to direct drainage water to the oppositely disposed water collecting receptacles in the opposite ends of the tray;

Figure 2 is a front elevation of the tray being shown partly broken away and in section;

Figure 3 is a sectional view taken on the line 3—3 of Figure 1;

Figure 4 is a plan view of a slightly modified form of tray having flutes on the shield sloping forwardly from top to bottom and spaced rearwardly sloping flutes on the base separated from the flutes on the shield to form a transverse trough extending transversely of said bottom at the back thereof, and the troughs between the flutes on said bottom being sloped rearwardly;

Figure 5 is a front elevation of the tray shown in Figure 4, the same being partly broken away and shown in section;

Figure 6 is a sectional view taken on the line 6—6 of Figure 5;

5 10 15 20 25 30 35 40 45 50 55

Figure 7 is a second modified form of soap tray having spaced flutes on the shield merging with forwardly sloping flutes on the back portion of the bottom of the tray, and short rearwardly sloping flutes on the forward portion of the bottom of the tray forming a transversely extending channel between the said flutes to direct drainage water to the collecting receptacles formed in the opposite ends of the soap tray;

Figure 8 is a sectional view taken on the line 8—8 of Figure 7, and

Figure 9 is a top plan view of the soap tray shown in Figures 7 and 8.

Like characters of reference are used throughout the following specification and the accompanying drawings to designate corresponding parts.

In carrying out the invention, there is provided several modifications of the improved soap tray, all of which are integrally formed by molding or casting from any desired material, and all of which are provided with bottom sections generally denoted by the reference numeral 1 and interconnected backs or shields generally denoted by the reference numeral 2. Also, each modification is provided with the integrally formed oppositely disposed water drainage receptacles 3 and 4 formed in the opposite ends of the bottom 1.

Figures 1, 2 and 3 illustrate one form of soap tray having spaced flutes 5 extending forwardly from their tops to their bottoms and merging with the spaced flutes 6 which are formed in the bottom 1 and are inclined rearwardly from front to back, while the troughs 7 formed between the flutes 6 are sloped forwardly to merge with the transverse water directing passage 8 at the front of said bottom section 1, which directs the drainage water from a wet cake of soap when placed on the tray towards the opposite ends of the tray and into said water drainage collecting receptacles 3 and 4.

40 45 50 55

In Figures 4, 5 and 6, a slightly modified form of tray is illustrated, and is formed with spaced flutes 9 extending forwardly from their tops to their bottoms, and spaced flutes 10 on the bottom of the tray 1 which slope rearwardly to form the transverse water directing passage 11 at the rear of the bottom 1 between the flutes 9 and 10, while the troughs 12 between flutes 10 direct the drainage water to said passage 11 and into the water drainage collecting receptacles 3 and 4 at the opposite ends of said tray.

In Figures 7, 8 and 9 there is shown another slightly modified form of soap tray which is formed with a series of spaced perpendicular flutes

13 on the shield or back 2 which merge with the short forwardly sloping flutes 14 formed on the tray bottom 1. A series of rearwardly sloping short flutes 15 are formed on the front portion of the tray bottom 1, and provide a centrally disposed transversely extending water drainage passage 16 for directing the drainage water to the end water collecting receptacles 3 and 4. The troughs 17 between the flutes 14 and 15 are substantially level.

Apertures 18 will be formed through the back or shield 2 of each form of soap tray to receive a screw or other fastening device for supporting and attaching the soap tray upon a vertical surface.

It will be seen from the description and the accompanying drawings that there has been provided a highly efficient and ornamental form of soap tray which will be easily kept clean, and which will have no extraneous corners in which dirt may collect, as all edges and angles in the soap tray are rounded or curved, thus leaving no place for dirt to settle and accumulate.

While the preferred embodiment of the instant invention has been illustrated and described, it will be understood that it is not intended to limit the scope of the invention thereto, as many minor changes in detail of construction may be resorted to without departure from the spirit of the invention.

Having thus described my invention what I claim as new and desire to secure by Letters Patent of the United States is:

A soap tray comprising a vertically extending

5 back member and a horizontally extending front member integrally formed therewith, said back and front members constituting a substantially L-shaped tray, spaced flutes extending inwardly from said back member, forwardly inclined spaced longitudinally extending raised flutes carried by the rear portion of said front member and merging with said back member flutes, rearwardly inclined spaced longitudinally extending raised flutes carried by the front portion of said front member, a centrally disposed transversely extending water drainage passage formed in said front member between said forwardly and rearwardly inclined flutes, and depressions at the ends of said front member forming collecting receptacles for receiving water from said drainage passage.

CECIL HERMAN DANTZLER.
